UNITED STATES PATENT OFFICE.

JOHN H. BARR, OF NEW YORK, AND HERBERT A. CARHART, OF SYRACUSE, NEW YORK,
ASSIGNORS TO REMINGTON TYPEWRITER COMPANY, OF ILION, NEW YORK, A COR-
PORATION OF NEW YORK.

TYPE-WRITING MACHINE.

1,252,218.

Specification of Letters Patent. Patented Jan. 1, 1918.

Application filed November 11, 1916. Serial No. 130,804.

To all whom it may concern:

Be it known that we, JOHN H. BARR and HERBERT A. CARHART, citizens of the United States, and residents, respectively, of the 5 borough of Manhattan, city of New York, in the county of New York and State of New York, and Syracuse, in the county of Onondaga and State of New York, have invented, certain new and useful Improvements in Type-Writing Machines, of which 10 the following is a specification.

Our invention relates to typewriting machines, and it has for its principal object to provide an improved carriage brake, more 15 especially designed for use in connection with the tabulator to regulate or lessen the velocity with which said carriage runs when released from its escapement.

To the above and other ends our invention 20 consists in certain features of construction and combinations and arrangements of parts, all of which will be fully set forth herein and particularly pointed out in the claims.

25 In the accompanying drawings,

Figure 1 is a front to rear vertical sectional view, on a reduced scale, of a typewriting machine having our invention embodied therein.

30 Fig. 2 is a view similar to part of Fig. 1 but on a larger scale and showing our brake mechanism in normal position by full lines and by broken lines in operated position.

Fig. 3 is a rear elevation, partly in section, on the line α α of Fig. 2.

Fig. 4 is a perspective view of our brake mechanism, said view made in two sections and condensed.

In all of the figures, parts have been omitted or broken away as has been found convenient.

We have illustrated our invention in its application to a Smith Premier No. 10 typewriter, the main frame of which machine 45 comprises side plates 1, a top plate 2, a keyboard plate 3, and a rear cross bar or plate 4, the last connecting the side plates 1 at the base of the machine. The plate 5 is mounted in a carriage 6 which runs on a 50 stationary rail 7 through the instrumentality of balls 8, said rail being mounted on standards 10 rising from the top plate 2. The carriage is fed by a spring 11 mounted in a spring drum 12 and operating a large gear

wheel 13 which meshes with a feed rack 14 55 secured to the carriage.

The carriage feed mechanism, including the spring drum and the escapement and their connections, is all mounted in a housing comprising a front vertical plate 15 and 60 a rear vertical plate 16, said housing being secured to the underside of the top plate 2. The spring drum 12 and the gear 13 are mounted on a shaft 17 in said housing and on said shaft there is also loosely mounted 65 a companion gear 18 which meshes with the feed rack 14 and also with a pinion 20, which pinion is an integral part of a sleeve 21 mounted with freedom to turn on a shaft 22, which at its rear end is journaled on a pivot 70 screw 23 passing through the plate 16 and at its forward end is journaled on another pivot screw 24 passing through a bracket 25 secured to the front face of the forward frame plate 15. On the forward end of the 75 shaft 22 is rigidly mounted an escapement wheel 26 which is controlled by feed dogs 27 mounted on a dog rocker 28 pivoted at 30 in depending branches of the bracket 25. This dog rocker is arranged to be oscillated 80 by the universal bar and space key of the machine, which parts, however, are not shown in the drawing. The pinion 20 and sleeve 21 are normally connected with the shaft 22 by means of a ratchet-toothed 85 clutch, of which the pinion 20 constitutes one member. The other member of said clutch consists of a sleeve 31 slidably mounted on said shaft 22 and having a tongue 32 (Fig. 2) engaging a groove in a flanged collar 33 rigid with the shaft. A compression spring 34 normally holds the clutch members in engagement, in which event the carriage is geared to the escapement wheel; but the carriage can be released from the escapement by sliding the clutch member 31 toward the rear, as indicated by broken lines in Fig. 2. To this end said clutch member is formed with a peripheral groove, in which lies the upper end of a release lever 35 which 95 is pivoted at 36 to a lug of the back frame bar 4.

One form of Smith Premier tabulator is illustrated in the drawing and it comprises a column stop bar 37 suspended from the 100 rear part of the carriage 6 by means of arms 38. This bar is formed on its front and rear faces with vertical grooves into which can

be inserted a plurality of column stops 40, each having one or more stop lugs 41 projecting downward therefrom, said stop lugs being out of alinement with one another for the purpose of column selection. Coöperating with said stop lugs is a key operated stop 42 extending into the base of the machine where it is suitably connected with a transverse rock shaft 43, which is pivoted in lugs 44 of the frame bar 4. The details of the connection between said stop and shaft are not shown herein as this mechanism is in common use and is well known. Said connections are of such character that when the shaft 43 is rocked by the tabulator keys the stop 42 is projected upwardly into the path of one of the lugs 41.

The shaft 43 has an arm 45 projecting toward the front of the machine near the right-hand side of said machine, and a pin 46 projecting laterally from the forward end of said arm constitutes a universal bar overlying a group of four tabulator key levers 47 which are all pivoted at 48 to the right-hand side plate 1. The levers 47 are normally held up at their forward ends by a series of springs 50 secured to a bracket 51 which is fastened at 52 to the side plate 1. Said levers are of different lengths and each of them has pivoted to its forward end the stem 53 of a tabulator key 54.

In order to provide for the selection of any desired one of the column stops 40, the upper end of the stop 42 passes through a guide 55 which is pivoted at 56 to a bracket 57 depending from the top plate 2, the construction being such that said guide can be rocked toward the front or toward the back of the machine to bring the stop 42 into line with any desired lug 41. Said guide is in the nature of a lever of the first order having a depending arm 58 with a roller 60 thereon, said roller overlying the rear ends of the levers 47, which levers are formed at said rear ends with cams of different inclinations so that when any one of them is operated it moves the roller in one direction or the other to determine the position of the stop 42 in accordance with the particular key 54 that has been operated. The roller 60 and guide 55 are held normally in a middle position by means of a cam guide 61 constituting part of the rear end of a lever 62 lying beside the levers 47 and controlled by one of the springs 50. Said lever 62 has an ear 63 projecting upward therefrom at the rear of the pivot 48, and a pin 64, projecting from said ear, lies over all of the levers 47 so that when any of the keys 54 is operated the rear end of the universal lever 62 will be moved upward, thus releasing the roller 60 from the control of the cam 61 and placing it under the control of the cam on the rear end of the operated lever 47.

65 The tabulator mechanism can be of any

desired construction as far as our invention is concerned, and the one herein partially shown and briefly described will be found more fully set forth in the patent to Brown No. 937,414, dated Oct. 19, 1909. The whole construction is such that when any one of the keys 54 is depressed the guide 55 will be rocked toward the front or toward the back to bring the stop 42 into line with one of the lugs 41 and at the same time the shaft 43 will be rocked, with the result that said stop 42 will be moved upward into the path of the selected lug 41.

The carriage is released by the rocking of the shaft 43. This can be effected in various ways but as here shown said shaft has a depending arm 65 having a pin 66 projecting into a notch 67 in the lower end of the release lever 35, with the result that when said shaft 43 is rocked the lower end of the lever 35 is moved toward the front of the machine and the upper end of said lever and the clutch member 31 are moved toward the rear of the machine, all as indicated in broken lines in Fig. 2.

Our brake mechanism comprises a drum 70 on the sleeve 21, and a brake shoe which is caused by the universal rock shaft 43 to press against said drum. Said brake shoe comprises a piece of leather or other suitable material 71, mounted on the upper end of a sheet metal bar or link 72. Said link may have a block 73 of suitable material secured to its upper end in order to provide a wider face for the brake shoe. The bar 72 is suitably bent toward the rear and at its lower end it has an ear 74 bent off therefrom to accommodate a pivot pin 75 projecting from an arm 76 which is loosely mounted on the universal rock shaft 43 and projects therefrom toward the front of the machine. Said bar or link 72 is guided at its upper end in any suitable way, the means here shown comprising two slotted ears 77 bent off from a sheet metal plate 78 secured by screws 80 to the frame plate 15, said ears embracing by their slots the right-hand edge of the bar 72 and the left-hand end of an arm 81 of said bar 72. A second arm 82 is pivoted on the shaft 43 by the side of the arm 76, and said arm 82 has an ear 83 bent off therefrom beneath the arm 76 and an adjusting screw 84 is screwed upward through said ear with its upper end in contact with said arm 76. Said screw 84 may be provided with a lock nut 85. The arm 82 is curved upward at its forward end where it is formed with an ear 86 to which is connected one end of a contractile spring 87, the other end of which is connected with an arm 88 rigidly secured, as by a pin 90, to the shaft 43. The arm 88 has an ear 91 bent off therefrom and normally lying in contact with the upper edge of the lever arm 76.

When the parts are in normal position

shown in Figs. 1 and 4, and by full lines in Fig. 2, the spring 87 is under tension and tends to move the loose arm 82 upward; and the tension of said spring is transmitted by 5 said arm and the screw 84 to the loose arm 76 which carries the brake shoe; and said arm 76 is thus pressed into contact with the ear 91, which limits the motion of arm 76 under the force of spring 87. Said spring 10 87 and lug 91 thus normally hold the parts in fixed relation. Thus the spring constantly tends to apply the brake, but is normally prevented from so doing by the restraining means thus described. When a 15 tabulator key is operated, the arm 88 being rigid on the shaft 43, is moved upward and toward the back of the machine, partaking of the whole motion of the shaft 43. The spring 87 pulls the arm 82 after it and said 20 arm 82 moves the arm 76, thus moving the brake shoe 71 up against the drum 70. Said brake shoe comes into contact with said drum before the oscillation of the shaft 43 is completed, and said shoe and the arms 76 25 and 82 are thereby arrested so that these parts do not move as far as the arm 88. The continued motion of said arm 88 lifts the ear 91 off of the arm 76, and transfers the force of the spring 87 to the brake shoe, pressing 30 said brake shoe against the drum 70. It will be perceived that the degree of pressure thus brought about between the brake shoe and the drum can be regulated to a nicety by adjusting the screw 84. The normal position 35 of the brake shoe is determined by the contact of the lever 76 with the ear 91 but the tension on the spring 87 can be regulated by adjusting the screw 84, the result of which adjustment will be to move the lever arm 82 40 up or down independently of the lever arms 88 and 76. If the lever 82 be adjusted downward the tension on the spring will be increased and if it be adjusted upward the tension on the spring will be diminished. 45 When a tabulator key is operated the arms 88, 82 and 76 move together until the brake shoe and the parts positively connected therewith are arrested by said shoe coming against the drum 70, after which the lug 91 50 is lifted off of the lever 76 and the whole tension on the spring 87, whatever that may be, comes on the brake shoe. Said tension can be made much or little by suitable adjustment of the spring, which adjustment, in 55 the present instance, is made by adjusting the screw 84, as above explained. It will be noted that the lower end of the screw points toward the bottom of the machine where it is readily accessible for the use of a 60 screw driver without removing any of the parts. It will also be noted that, whereas one end of the spring 87 is connected with the brake, the other end is connected, not to the stationary framework, but to the arm 88 65 of the tabulator mechanism; and that the

stop 91 which normally limits the action of said spring, is also a part of said tabulator mechanism. As a result of this construction, said spring 87 does not resist the return of the tabulator mechanism to normal position 70 when a tabulator key is released after having been operated.

It will be perceived that our improved brake mechanism is constructed almost entirely of sheet metal, that it has few parts, 75 which are inexpensive to manufacture and which are effective for their purpose, and that the action of the brake can be very readily regulated after the machine has been assembled. The drum 70 is preferably made of a diameter greater than that of the pinion 20 so that the brake acts on a part of the machine that has a faster surface speed than the carriage itself. In other words, it has a little leverage on the carriage so that a less 80 degree of pressure is required than would otherwise be necessary. The leather brake shoe 71 is also preferably curved about the drum 70 and this increases the friction for a given amount of pressure. This is desirable 85 because, whereas the brake pressure comes directly from the spring 87, the tension of said spring has to be overcome by the finger of the operator acting on the key 54, and it is desirable not to put too heavy a resistance 90 on said key. At the same time the degree of pressure of the brake can be no greater than the tension of the spring, no matter how great the pressure on the key. If said key is operated to a sufficient extent to release the 95 carriage it will lift the ear 91 off of the lever 76 and cause the spring 87 to act on the brake shoe.

Various changes can be made in the details of our construction and arrangement 100 without departing from our invention.

What we claim as new and desire to secure by Letters Patent, is:—

1. In a typewriting machine, the combination with a brake member and a key, of an intermediate train of devices including a bodily movable spring having a tension normally to apply said brake member, and means for restraining the action of said spring until said key shall have been actuated, said spring constituting a connecting link between two other parts of said key-operated train. 110
2. In a typewriting machine, the combination with a brake member and a finger key, 120 of an intermediate train of devices including a bodily movable spring normally adapted to apply said brake at the initial operation of said key and after such application adapted also to yield during any further movement of said key and without materially affecting the braking pressure, said spring constituting a connecting link between two other parts of said key-operated train. 125

3. In a typewriting machine, the combination of a rotary member connected with the carriage feeding mechanism, a brake shoe adapted for application to said rotary member, a key lever, a train of devices between said key lever and said brake shoe comprising a bodily movable spring normally under tension and by the same tending always to apply said brake shoe, and a stop member for preventing such action until the said key shall have been actuated, said spring and stop member being interposed between two parts of said key-operated train.
4. In a typewriting machine, the combination of a rotary member connected with the carriage feeding mechanism, a brake shoe adapted thereto, an arm connected to lift said brake shoe, a coiled spring connected at one end to said arm, a second arm to which the other end of said spring is connected, said second arm being provided with means for preventing movement of the first arm by said spring until the said key shall have been actuated.
5. In a typewriting machine, the combination with a carriage, tabulator mechanism including a rock shaft, escapement mechanism, and carriage releasing means, of an arm fixed on said rock shaft, a second arm loose on said rock shaft, a friction brake controlled by said second arm, and a spring between said fixed arm and said loose arm.
6. In a typewriting machine, the combination with a carriage and tabulator mechanism including a rock shaft; of escapement mechanism, carriage releasing means operated by said rock shaft, an arm fixed on said rock shaft, a second arm loose on said rock shaft, a friction brake controlled by said second arm, a spring between said fixed arm and said loose arm, and means adjustable to regulate the tension of said spring.
7. In a typewriting machine, the combination with a carriage and tabulator mechanism including a rock shaft, of escapement mechanism, carriage releasing means operated by said rock shaft, a friction brake, an arm loose on said rock shaft and connected to said brake, a second arm loose on said rock shaft, means for adjusting the relation between the two said loose arms, an arm fast on said rock shaft, and a spring connecting said fast arm with the second recited loose arm.
8. In a typewriting machine, the combination with a carriage and tabulator mechanism including a rock shaft, of escapement mechanism, carriage releasing means operated by said rock shaft, a friction brake, an arm loose on said rock shaft and connected to said brake, a second arm loose on said rock shaft, means for adjusting the relation between the two said loose arms, an arm fast on said rock shaft, a spring connecting said fast arm with the second recited loose arm,

and means for limiting the motion of the first mentioned loose arm with respect to said fast arm.

9. In a typewriting machine, the combination with a carriage and tabulator mechanism including a series of tabulator keys and a universal member operated by said keys, of escapement mechanism, carriage releasing means controlled by said tabulating mechanism, a brake mechanism including a part moving with the carriage when said carriage is released, a friction brake, a device operated by said universal member of the tabulator mechanism, a spring connection between said device and said brake, and means for regulating the tension of said spring connection without varying the normal position of said brake.

10. In a typewriting machine, the combination with a carriage, tabulator mechanism including a plurality of tabulator keys and a universal member operated by said keys, escapement mechanism, and carriage releasing means controlled by said universal member, of carriage brake mechanism including a brake shoe, a device operated by said universal member of the tabulator, a second device connected with said brake shoe and occupying a fixed normal position relative to the first mentioned device, and a pressure-transmitting spring connected with one of said devices and having an adjustable connection with the other of said devices, whereby the tension of said spring can be regulated.

11. In a typewriting machine, the combination with a carriage, tabulator mechanism, escapement mechanism, and a carriage release device, of carriage brake mechanism including a brake shoe, an arm adapted to be oscillated by an operation of the tabulator mechanism, a second arm connected with the first mentioned arm by a spring, a third arm connected with said brake shoe, an adjustable connection between said second and third arms, and means for limiting the motion of said third arm with relation to said first arm under the impulse of said spring.

12. In carriage brake mechanism for typewriting machines, the combination of a brake shoe, a hand operated rock shaft 43, a loose arm 76 connected with said brake shoe, a loose arm 82 having adjustable connection with said arm 76, an arm 88 fast on said rock shaft and connected by a spring 115 with said arm 82, and a device 91 to limit the motion of the arm 76 with relation to the arm 88.

13. In a typewriting machine, the combination with a carriage, a shaft 22, escapement mechanism including a wheel connected with said shaft, a drum 70 sleeved on said shaft 22 and geared to said carriage, a clutch connection between said drum and said shaft, a brake shoe capable of being 125 130

5 applied to said drum, a link 72 for operating said brake shoe, tabulator mechanism including a rock shaft 43, means whereby said rock shaft operates said clutch, an arm loose on said rock shaft and controlling said link 72, an arm fast on said rock shaft, a spring 87 for communicating spring pressure from said fast arm to said loose arm when the tabulator is operated, and means for regulating the tension of said spring.

10 14. In a typewriting machine, the combination with a carriage, escapement mechanism, tabulator mechanism and a carriage release device; of a drum geared to said 15 carriage, a brake shoe partially encircling said drum, and a bodily movable adjustable spring acting at one end on said brake shoe

and connected at its other end to said tabulator mechanism.
